(57) **CLAIM**

We claim the ornamental design for a cap, as shown and described:

DESCRIPTION

FIG. 1 is a perspective view of the cap.

FIG. 2 is a top view of the cap.

FIG. 3 is a bottom view of the cap.

FIG. 4 is a side view of the cap and is identical to an opposite side view, a front view, and a front rear view of the cap, not shown in the FIGS. 1-5; and,

FIG. 5 is a cross sectional view of the cap taken along line 5-5 of FIG. 2 to illustrate the configuration of the exterior surface of the cap not apparent from the other views of the cap.

The broken lines describing a sanitary end, as shown in FIG. 1, are for illustrative purposes only and form no part of the claimed design.
